GRINDING WHEEL POSITIONING MECHANISM

Carl G. Flygare, Worcester, Mass., assignor to
Norton Company, Worcester, Mass., a corporation of Massachusetts

Application August 15, 1935, Serial No. 36,385

4 Claims. (Cl. 51—72)

This invention relates to grinding machines, and more particularly to a grinding wheel positioning mechanism.

One of the objects of this invention is to provide a simple and thoroughly practical grinding wheel positioning mechanism.

It is another object of this invention to provide a wheel spindle positioning mechanism which is compact in form and simple in construction and 10 serves to enable the grinding wheel to be moved axially.

Another object of this invention is to provide a wheel spindle positioning mechanism which is manually controlled to permit the grinding wheel 15 to be readily positioned up against a shoulder to grind the end face of the shoulder.

Another object of this invention is to provide a wheel spindle positioning mechanism which is manually controlled and which serves to locate 20 and hold the spindle in a predetermined adjusted position relative to the work.

Another object of this invention is to provide a wheel spindle positioning mechanism which is controlled by a manually operable lever to readily 25 position the grinding wheel to split the spark in a crankshaft grinding operation.

Other objects will be in part obvious or in part 30 pointed out hereinafter.

This invention accordingly consists in the features of construction, combinations of elements, and arrangements of parts as will be exemplified in the structure to be hereinafter described, and the scope of the application of which will be indicated in the following claims.

In the accompanying drawings in which is 35 shown one of various possible embodiments of the mechanical features of this invention,

Fig. 1 is a vertical sectional view taken through a grinding wheel slide showing the wheel spindle, 40 bearings, and positioning mechanism;

Fig. 2 is a fragmentary sectional view, on an enlarged scale, of the wheel spindle positioning mechanism;

Fig. 3 is a cross sectional view taken approximately on the line 3—3 of Fig. 1;

Fig. 4 is a fragmentary elevation, on an enlarged scale, of the lever control and stop device for the wheel spindle positioning mechanism;

Fig. 5 is a fragmentary plan view to show the 50 applicability of this invention to a crank grinding operation;

Fig. 6 is a fragmentary plan view showing the application of this invention to a shoulder grinding operation, such as grinding the shoulder 55 of a roll;

Fig. 7 is a vertical sectional view taken approximately on the line 7—7 of Fig. 2; and

Fig. 8 is a fragmentary plan view of the connection between the screw and yoke.

The embodiment of the invention selected for

illustration comprises a grinding machine having a base 10 which supports a transversely movable wheel slide 11 on a flat way 12 and a V-way 13. The wheel slide 11 is arranged to be moved transversely on the flat way 12 and V-way 13 by means of a feeding mechanism including a half nut 15 which depends from the under side of the wheel slide 11. The half nut 15 engages a cross feed screw 16 which may be rotated by any well-known feeding mechanism, such as for example 10 that shown in the expired patent to Norton No. 762,838 dated June 14, 1904.

The wheel slide 11 is provided with bearings 20 and 21 which serve to rotatably support a grinding wheel spindle 22. A grinding wheel 23 is 15 mounted at one end of the spindle 22, and a driving pulley 24 is mounted at the opposite end thereof. The driving pulley 24 may be driven by a belt from any suitable source of power, such as an overhead belt drive (not shown) or a motor 20 on the wheel slide (not shown).

To obtain the main object of this invention, it is desirable to provide a simplified means of grinding a shoulder on a work piece and also to split the spark or equalize the side grinding by opposite sides of the grinding wheel 23 in a crankshaft grinding operation. This is preferably accomplished by providing a grinding wheel spindle which is capable of an axial or longitudinal movement within its bearings and providing a wheel spindle positioning mechanism by which the wheel spindle may be readily moved axially within its bearings to position the wheel in the desired operative relation with the work piece being ground. Such a mechanism is preferably manually operated and arranged so that the grinding wheel may be readily and accurately positioned 30 against a shoulder or the grinding wheel may be moved to split the spark and equalize the side grinding of the wheel in grinding the cheeks of 35 a crankpin in a crankshaft grinding operation.

In the embodiment of the invention illustrated in the drawings, the wheel spindle is provided with a rotatable collar 35 which is rotatably mounted on the spindle 22 against a shoulder on the spindle 36 by means of a thrust collar 37. A yoked member 38 is pivotally mounted on a stud 39 in the wheel slide 11 and is connected with the collar 35 by means of screws 40 and 41 which are screw-threaded into the yoked member 45 38. The screws 40 and 41 are provided with cylindrical end portions 42 and 43 which engage holes 44 and 45 in the collar 35. It will be readily apparent that when the yoked member 38 is rocked on its pivot 39, the pins 42 and 43 through collar 35 will transmit an endwise axial positioning movement of the spindle 22.

In order that the endwise positioning movement of the wheel spindle may be readily controlled and the spindle may be moved to a prede- 60

terminated position by movement of a manually operable control lever and retained in the adjusted position during the grinding operation, a suitable, readily accessible, manually operable control is provided. The yoked member 38 is provided with a rearwardly extending arm 46 which is connected by a vertically movable stud 47 with a transversely movable bushing 48 carried by the head 49 of a screw 50. The head 49 is formed of two parts which are arranged to support the transversely movable bushing 48. An end cap 51 is held on the open end of the head 49 by means of screws 52. The end cap 51 is provided with a longitudinally extending way 53 which mates with correspondingly shaped groove 54 in the bushing 48. The bushing 48 is arranged to slide transversely within the head 49 as the yoke 38 is oscillated.

The screw 50 is screw threaded into a rotatable nut 55 which is supported in a bearing 56. The bearing 56 is held in a depending projection 57 of a cover plate 58 on the upper surface of the wheel slide 11. The depending projection 57 is provided with a cylindrical bore 59 of a size to support the bearing 56. The depending portion 57 is slotted at its lower extremity and is provided with a pair of transversely extending clamping screws 60 and 61 which serve to lock or clamp the bearing 56 in a position within the depending portion 57. The nut 55 is provided with a reduced threaded portion 65 which serves to support a thrust collar 66. The other end of the nut 55 is provided with an integrally formed bevel gear 67. The rear face 68 of the gear 67 serves as an end thrust member to bear against the end of the bearing 56. The thrust collar 66 is held in adjusted position by means of the lock nuts 70 and 71. The pitch of the screw threads 50 and the nut 55 are such that when the bevel gear 40 67 is rotated, the screw will be moved endwise to position and hold the grinding wheel in a predetermined position relative to the work. This movement is transmitted through the stud 47 to cause a rocking movement of the arm 46 which 45 serves to rock the yoked member 38 about its pivot stud 39. This movement of the yoked member 38 transmits a corresponding movement through the screws 40 and 41 to move the collar 35 and transmit an endwise positioning movement to the wheel spindle 22 and the grinding wheel 23.

In order to readily rotate the nut 55, a manually operable control device is provided on the upper portion of the wheel slide. A rotatable shaft 70 is mounted in a vertically extending boss 71 on the plate 58. The lower end of the shaft 70 is provided with a bevel gear 72 which meshes with bevel gear 67. The bevel gear 72 is locked on a reduced portion 73 of the shaft 70 by means 60 of a washer 74 and a nut 75 which is threaded on a reduced threaded portion 76 of the shaft 70. The shaft 70 is provided with an integral flange 80 and integral reduced portion 81. A plate 82 is mounted on the portion 81 of the shaft 70 and 65 is held in a fixed position relative to flange 80 by means of screws 83.

A control lever 85 is connected to a yoked member 86 which straddles a block 87 and is pivotally connected thereto by means of a stud 88. The block 87 is provided with an aperture 89 which rotatably fits the portion 81 of the shaft 70. The block 87 is held on the portion 81 of the shaft 70 by means of a collar 90 and a nut 91 which is threaded on a reduced threaded portion 92 of 75 the shaft 70. The block 87 is freely rotatable on

the portion 81 of the shaft 70 and its lower surface rests on the upper surface of plate 82. The nut 91 is adjusted to hold the collar 90 in the desired position to support and hold the block 87 against vertical or endwise movement.

The yoked portion 86 of the lever 85 is provided with a pawl 100 which is held in a fixed position thereon by means of a nut 101 and is arranged to engage any one of a series of notches 102 in the plate 82. When the pawl 100 is in engagement with any one of the notches 102 in plate 82, movement of the lever 85 serves to transmit a rotary motion to the shaft 70 and through bevel gears 72 and 67 causes a rotation of the nut 55 and an endwise movement of the screw 50 to 15 rock the yoked member 38 and thereby cause an endwise positioning movement of the wheel spindle 22 and the grinding wheel 23.

The lever 85 has been shown in Fig. 1 in a position at 90° to its normal position for the sake of clarity of illustration. The normal position of the lever 85 is at substantially right angles to the spindle 22 so that the lever 85 projects toward the front of the machine within easy reach of the operator.

The lever 85 may be swung through a considerable distance to cause a positioning movement of the wheel 23. Due to the reduction gearing and the pitch of the screw 50, a great reduction is obtained between the lever 85 and the spindle 22, so that the wheel 23 may be moved and positioned precisely in a predetermined position relative to the work piece being ground. If a greater movement of the wheel spindle is desired than can be obtained by the normal movement of the lever 85, the lever 85 may be moved to its extreme position in either direction and the lever 85 then rocked about the pivot 88 to disengage the pawl 100 from the notch 102 and the lever 85, so that the yoked member 86 and the block 87 may then be rotated on the portion 81 of shaft 70 relative to the notched plate 82 until the pawl 100 is aligned with the next notch 102 on the plate 82 and the lever 85 is then swung downwardly about its pivot 88 so that the pawl 100 engages the next notch 102. This positioning of the lever 85 relative to the plate 82 may be continued to the desired extent to cause the wheel spindle 22 and the grinding wheel 23 to move into the desired position relative to the work.

The periphery of the index or notched plate 82 may be provided with a graduated scale in order that the operator may readily observe the extent of movement of the wheel, if desired. An index finger or pointer 105 is fixedly mounted on the hub 71 and extends upwardly into alignment with the graduations on the plate 82.

It is desirable to provide a suitable friction device which may be adjusted to retard the rotation of the shaft 70. This is preferably accomplished by means of a friction ring or brake 106 which is preferably formed in two halves having a central aperture 107 arranged to fit and engage the periphery of the flange 80 on the shaft 70. The two halves of the friction ring or brake 106 are connected together by means of bolts 108 and 109. Each of the bolts 108 and 109 is provided with a tension device comprising a spring 110 which surrounds an extension of the bolts 108 and 109 and is held in adjusted tension thereon by means of lock nuts 111. By adjusting the lock nuts 111, the tension of the springs 110 may be adjusted so that the required friction is obtained between the ring 106 and the flange 80.

In order to limit the extent of positioning movement of the grinding wheel 23, it is desirable to provide a suitable stop device which prevents axial positioning movement of the grinding wheel 23 beyond the desired distance. This is preferably accomplished by providing a stop lug 115 on the friction or brake ring 106. The stop lug 115 is arranged in the path of a similar stop lug 116 formed as an integral part of the hub 11. When the stop lug 115 engages the lug 116, a further movement of the lever 85 can only be obtained against the friction of the brake ring 106, thereby giving the operator a warning that the wheel should not be moved further in an axial direction.

In the operation of the wheel spindle positioning mechanism, the operator rotatably mounts a cylindrical work piece, such as a roll 26 or a crankshaft 30, on the work supporting table (not shown) and by means of the usual table positioning mechanism positions the work in an approximate position relative to the grinding wheel. The grinding wheel is then fed transversely into operative engagement with the portion of the work to be ground by rotation of the screw 16 through the usual feed mechanism (not shown). The lever 85 is then moved to cause the wheel spindle 22 to move axially so as to position the side face of the wheel 23 in the desired relation with the shoulder 27, or the cheek 32 and 33 of the crankpin 31 which is to be ground.

In grinding a crankpin or a main bearing of a crankshaft, the crankshaft is rotatably mounted in operative position on the work table and the work table is then moved longitudinally to position the crankshaft in the approximate operative position relative to the grinding wheel. The wheel is then fed transversely toward the pin or bearing to be ground. When the wheel comes into approximate engagement with the cheeks of the pin or bearing, the lever 85 is swung in either direction to cause an endwise positioning movement of the wheel 23 to split the spark or equalize the side grinding on opposite cheeks of the pin or bearing to be ground.

It will thus be seen that there has been provided by this invention a wheel spindle positioning mechanism in which the various objects hereinabove set forth together with many thoroughly practical advantages are successfully achieved.

As various possible embodiments may be made of the above invention and as many changes might be made in the embodiment above set forth, it is to be understood that all matter hereinbefore set forth, or shown in the accompanying drawings, is to be interpreted as illustrative and not in a limiting sense.

Having thus described my invention, what I claim as new and desire to secure by Letters Patent is:

1. In a grinding machine, a transversely movable wheel slide, spindle bearings in said slide, a rotatable wheel spindle supported in said bearings and arranged for a longitudinal axial positioning movement relative thereto, a rotatable grinding wheel carried by said spindle, a rotatable end thrust member on said spindle, a yoked member pivotally mounted on said slide and arranged to move the spindle axially within its bearings, a nut and screw mechanism to move said yoked member, and means including a man-

ually operable lever to actuate said nut and screw to positively slide the wheel spindle in either direction within its bearings so as to position the grinding wheel into a predetermined position relative to the work piece and to positively hold it in said adjusted position during grinding.

2. In a grinding machine, a transversely movable wheel slide, spindle bearings on said slide, a rotatable wheel spindle supported in said bearings and arranged for a longitudinal axial positioning movement relative thereto, a rotatable grinding wheel on said spindle, an end thrust member carried by said spindle, a yoked member pivotally mounted on said slide and operatively connected to said thrust member to move the 10 spindle within its bearings, a screw arranged to move said yoked member, a rotatable nut associated with said screw and arranged to move the screw endwise, and means including a manually operable lever to rotate said nut so as to 15 positively move the spindle in either direction within its bearings to position the grinding wheel into a predetermined position relative to the work piece, said parts being so arranged that the grinding wheel may be manually positioned 20 in a predetermined position relative to the work piece and positively held in said predetermined position during grinding.

3. In a grinding machine, a transversely movable wheel slide, spindle bearings on said slide, 30 a rotatable wheel spindle supported in said bearings and arranged for a longitudinal axial positioning movement relative thereto, a rotatable grinding wheel on said spindle, an end thrust member carried by said spindle, a yoked member 35 pivotally mounted on said slide and operatively connected to said thrust member to move the spindle within its bearings, a screw arranged to move said yoked member, a rotatable nut associated with said screw and arranged to move the 40 screw endwise, a reduction gear mechanism operatively connected to rotate said nut, and means including a manually operable lever to rotate said gearing so as to move the spindle within its bearings to position the grinding wheel into a 45 predetermined position relative to the work piece, said parts being so arranged that the grinding wheel may be manually positioned in a predetermined position relative to the work piece and positively held in said predetermined position 50 during grinding.

4. In a grinding machine, a transversely movable wheel slide, spindle bearings carried by said slide, a rotatable wheel spindle in said bearings and arranged for a longitudinal axial positioning 55 movement relative thereto, a rotatable grinding wheel carried by said spindle, a thrust member carried by the spindle, a yoked member pivotally connected to said slide and operatively connected to move said spindle longitudinally, a screw operatively connected to move said yoked member, a rotatable nut operatively connected to move said screw endwise, a reduction gear mechanism, a manually operable pivotally mounted lever arranged to turn said gear to move said spindle 60 to position the grinding wheel in a predetermined position relative to the work piece and to hold it in adjusted position during grinding, and means including a pawl and notched wheel interposed between said lever and gearing to adjust 65 the position of said spindle relative to said lever.

CARL G. FLYGARE.
